United States Patent Office

Des. 188,510
Patented Aug. 2, 1960

188,510

CIGARETTE DISPENSER

Michel Verdier, Chateau de Saint-Prex, Saint-Prex,
Vaud, Switzerland

Filed Sept. 9, 1959, Ser. No. 57,487

Claims priority, application Switzerland Apr. 5, 1959

Term of patent 14 years

(Cl. D52—3)

The single figure is a perspective view of a cigarette dispenser embodying my new design.

The undisclosed end of the dispenser is substantially the same in appearance as the end shown, and the rear is plain.

I claim:

The ornamental design for a cigarette dispenser, substantially as shown and described.
